UNITED STATES PATENT OFFICE.

JOHN B. HADAWAY, OF SWAMPSOFT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

WELT-BEATING MACHINE.

1,290,179.

Specification of Letters Patent.

Patented Jan. 7, 1919.

Application filed April 2, 1915. Serial No. 18,692.

To all whom it may concern:

Be it known that I, JOHN B. HADAWAY, a citizen of the United States, residing at Swampscott, in the county of Essex and 5 State of Massachusetts, have invented certain new and useful Improvements in Welt-Beating Machines; and I do hereby declare the following to be a full, clear, and exact description of the invention, such as will enable others skilled in the art to which it 10 pertains to make and use the same.

This invention relates to welt beating machines for beating out the welt of a fasted shoe and, more particularly to machines of 15 this class in which the welt beating means has an intermittent gripping engagement with the welt. Certain features of the invention, however, are not limited to welt beating machines in which the welt beating means has this particular mode of operation but may be embodied with advantage 20 in other welt beating machines.

Welt beating machines of the type at present in common commercial use are provided 25 with a welt support and with a welt beating hammer which is vibrated with great rapidity to beat out the welt as it is advanced across the upper surface of the welt support.

In such machines the welt is fed between 30 the strokes of the hammer when the hammer is disengaged from the welt. Young or inexperienced operators are very frequently employed to operate these machines and the welt is often advanced so rapidly through 35 the machine that the operation is not sufficiently performed. It is desirable that the welt should be beaten out more or less at all points so that it will lie flat in substantially the plane of the insole, and the welt is often 40 slighted by the operator at certain points particularly along the sides of the shoe so that it is not in proper condition when the outsole is applied thereto. To obviate this difficulty it has been proposed to provide 45 machines of this type with a feed mechanism arranged to advance the welt a predetermined uniform distance between the strokes of the hammer. It is not desirable, however, 50 that the welt should be fed at the same speed at all points since certain portions thereof, such as the toe, ordinarily require a more extended beating than other parts.

One object of the present invention is to

produce a welt beating machine of the type having welt beating means acting to grip 55 the welt intermittently in which it will be impossible for the operator to advance the welt more rapidly than a predetermined speed and upon which the welt beating operation may be performed in an efficient and 60 reliable manner.

Other objects of the invention are to improve the construction and mode of operation of welt beating machines and to produce a machine upon which the welt beating 65 operation may be performed with the exercise of a less degree of skill and care on the part of the operator than is required in the operation of machines heretofore produced.

With this object in view, one feature of 70 the invention contemplates the provision in a welt beating machine having welt beating means acting to grip the welt intermittently of means for limiting the speed at which the welt may be fed through the machine arranged to allow the feed to be controlled by the operator within the limiting speed. This provision prevents the welt 75 from being slighted or left unbeaten at any point and at the same time allows the operator to control the feed so as to subject certain portions of the welt to a more extended beating action than other portions thereof.

Another feature of the invention contemplates the provision, in combination with 80 means for limiting the speed at which the welt may be fed through the machine, of means for varying the limiting speed during the operation of the machine.

In the present embodiment of the invention 85 means is provided for varying the pressure of the welt beating means on the welt during the operation of the machine so that certain portions of the welt may be subjected to a heavier beating action than other portions thereof and another feature of the invention 90 contemplates the provision of a connection between the pressure varying means and the mechanism for controlling the speed limiting means arranged to cause a decrease 95 in the limiting speed upon increasing the pressure of the welt beating means on the welt. This provision insures a more extended beating of the welt at the refractory portions thereof where the pressure of the 100 welt beating means is increased.

Other features of the invention consist of certain novel and improved constructions, arrangements and combinations hereinafter described and particularly pointed out in 5 the claims, the advantages of which will be obvious to one skilled in the art.

The features of the invention will be readily understood from an inspection of the accompanying drawings and the following detailed description in which is illustrated and described a welt beating machine embodying the invention in its preferred form.

In the drawings, Figure 1 is a view in side elevation of the machine; Fig. 2 is a view 15 in front elevation of the machine with the welt support in lowered position illustrating the parts in the positions which they assume at one point in the operation of the machine; Fig. 3 is a view similar to Fig. 2 20 illustrating certain of the parts in different positions; Fig. 4 is a view in front elevation of the machine illustrating the parts in the positions which they assume at substantially the same point in the operation as illustrated 25 in Fig. 3, but with the welt support in raised position; and Fig. 5 is a detail view of the treadle mechanism for elevating the welt support and controlling the operation of the slashing knife.

30 The welt beating machine illustrated in the drawings has the same general construction and mode of operation as the welt beating machine shown and described in the patent to Hadaway, Serial No. 875,171, 35 dated December 31, 1907. The machine is provided with a welt support indicated at 2 which is shaped to enter the crease between the upper and welt of a lasted shoe so as to support the welt upon its upper surface and with a vibratory welt beating hammer indicated at 4 arranged to deliver blows on the welt as it is advanced across the upper surface of the welt support. The hammer is secured to the lower end of a hammer 40 rod 6 mounted to slide in suitable guides in the forward end of the hammer lever 8. To cushion the blows delivered by the hammer upon the welt a coiled spring 10 mounted in a cylindrical chamber in the forward 45 end of the hammer lever surrounds the hammer rod and engages at its upper end the upper face of the chamber in the hammer lever and at its lower end a shoulder on the hammer rod. The downward movement 50 of the hammer in the hammer lever is limited by a clamping nut 12 threaded upon the upper end of the hammer rod. The hammer lever 8 is mounted to oscillate upon a short shaft 14 supported on the frame of 55 the machine and is rapidly oscillated to vibrate the hammer by means of an eccentric fixed to the main shaft 16 of the machine and operating within an eccentric block 18 mounted in the forked rear end of 60 the hammer lever.

The machine is provided with a welt slashing knife indicated at 20 which, except as hereinafter described, has substantially the same construction, arrangement and mode of operation as the welt slashing knife 70 of the machine illustrated and described in the Hadaway patent referred to above. The welt slashing knife is secured to the forward end of the reciprocating slide 22, the rear end of which is connected with an oscillatory lever 24 pivoted at 26 and provided with a cam roll 28 engaging a cam groove 30 in a cam disk 32 mounted to turn upon a rearwardly extending shaft 34 fixed in the frame of the machine. The main shaft 80 16 of the machine carries a worm meshing with a worm wheel 36 mounted on the rearwardly extending shaft 34 alongside the cam disk 32 and a sliding clutch pin 38 mounted in the cam disk 32 and arranged to be moved into and out of clutching engagement with the worm wheel 36, is provided to connect the cam disk with the worm wheel at certain times so that the cam disk may be actuated to operate the welt 90 slashing knife. The action of the clutch pin is controlled by a wedge 40 mounted upon the extremity of a lever 42, pivoted upon the shaft 44 and normally held in elevated position by a tension spring 46 to maintain the clutch pin 38 disengaged from the worm wheel 36. The lever 42 may be depressed to allow the clutch pin to be actuated by the spring 48 to engage the worm wheel 36 and thereby connect the cam disk 100 with the worm wheel by means of a treadle connected with the lever by a treadle rod 50.

In order that the pressure of the welt beating hammer on the welt may be varied at different points in the welt, the welt support is mounted in the machine so that it may be adjusted vertically. To this end the welt support is mounted upon the forwardly extending arm of a hanger 52 which is pivoted upon the shaft 14 of the hammer lever. To support the hanger 52 an arm 54 is fixed to a stud 56 mounted in bearings in the hanger 52 and engages at its rear end the curved face 58 of a support 60 adjustably pivoted on the shaft 44. The lower end of the support 60 is supported by means of an adjustable abutment screw 62 threaded into the support 60 and engaging at its lower end an abutment 64 on the frame. The support 60 is adjusted so that the lower portion of the curved face 58 thereof is nearer the axis about which the arm 54 swings than the upper portion of said face. With this construction the forwardly extending arm of the hanger 52 will be lifted 115 to elevate the work support by swinging the arm 54 downwardly about its pivot 56. To maintain the arm 54 normally in elevated position so that the work support is normally lowered, a spring 66 is coiled about 120 the pivot 56.

the shaft 56, one end of said spring being fast to the shaft and the other engaging a pin 68 projecting from the hanger 52. To enable the operator to depress the arm 54 to 5 elevate the welt support, the arm is connected by a treadle rod 70 with a suitable treadle.

The distance which the welt may be advanced between the strokes of the hammer is limited positively to limit the speed at which the welt may be fed through the machine by means of a feed limiting foot 72 arranged to engage the upper surface of the welt. This foot 72 is pivoted by a pin 74 to the laterally extending arm of a rocking frame 76 mounted on the shaft 78 supported in the upwardly extending arm 80 of the hanger 52. During each cycle of operations of the machine the foot 72 is depressed into engagement with the welt before the hammer is lifted from the welt as shown in Figs. 3 and 4 and is held in engagement with the welt between the strokes of the hammer.

After the hammer has again engaged the welt the foot is lifted from the welt as shown in Fig. 2. These movements are imparted to the foot 72 by suitable actuating mechanism connected with the rocking frame 76. It will be noted that with this mode of operation of the hammer and the foot 72, the welt is at all times engaged either by the foot or the hammer. Limiting stops are provided to limit the swinging movement of the foot 72 along the line of feed and thereby to limit the distance which the welt may be advanced between the strokes of the hammer, the foot being engaged with the rear stop when it initially engages the welt and being swung over against the forward stop 40 by the feed movement of the welt as the welt is advanced between the strokes of the hammer. The frame 76 is actuated to depress the feed limiting foot 72 into engagement with the welt by means of a spring 82 coiled 45 about the shaft 78, one end of which engages the arm 80 of the hanger 52 and the other end is made fast in a bore in the frame 76. The rocking frame 76 is actuated to lift the feed limiting foot from the welt in timed

50 relation to the movements of the hammer during each cycle of operation by mechanism comprising a bar or link 88 connected with a laterally extending arm 90 on the frame 76 by means of a pin 92 engaging in a slot 94 in the link. The lower end of the link 88 is pivotally connected at 96 with the arm 98 of a bell-crank lever pivoted on the shaft 44. The other arm 100 of this bell-crank lever is slotted to receive a block 102 mounted upon a pin 104 carried on the end of an arm 106 fixed to the shaft 14 upon which the hammer lever is mounted. The hammer lever is also fixed to this shaft so that the shaft is rocked by the oscillating 60 movements of the hammer lever. Through

the connections described suitable movements are imparted from the hammer lever shaft to the rocking frame 76 to lift the feed limiting foot from the welt in timed relation to the movements of the hammer as 70 above described. The pin and slot connection is provided between the link 88 and the arm 90 of the frame 76 to allow for lost motion between these parts as the hammer lever continues its movement after the feed limiting 75 foot 72 has been lowered into engagement with the work. The frame 76 is mounted upon the hanger 52 which carries the welt support so that the forward end of the frame upon which the feed limiting 80 foot is mounted is raised and lowered with the welt support. The parts of the mechanism for lifting the feed limiting foot are arranged so that the center of the shaft 14 and the center of the pivotal connection 96 85 are substantially in line with the point of connection of the upper end of the link 88 with the arm 90. With this construction the swinging of the hanger 52 about the shaft 14 to raise and lower the welt support will 90 produce substantially no angular movement of the frame 76 on the shaft 78 so that the feed limiting foot 72 is raised and lowered substantially the same distance as the welt 95 support.

As above stated, in order to limit the distance which the welt may be fed while the hammer is disengaged from the welt, limiting stops are provided for limiting the swinging movement of the foot 72. In the 100 construction illustrated the rear stop indicated at 108 is secured upon the forward end of the hammer lever by means of a screw 110 and limits the swinging movement of the foot 72 in a direction opposite to the direction of feed. The foot 72 when it is lifted from the welt is engaged with the rear stop 108 by a spring 112 mounted in a suitable bore in the frame 76 and engaging an arm 114 formed on the foot 72. The swinging 105 movement of the foot 72 in a forward direction is limited by means of a stop shoulder 116 formed on the welt beating hammer 4. With this construction as the feed limiting foot 72 is depressed into engagement with the welt it is held against the rear stop 108 by the spring 112 and its position in the direction of feed at the time at which it engages the welt is determined by this stop. As the hammer is disengaged from the welt 115 the welt is advanced along the upper surface of the welt support until the foot 72 engages the forward stop 116 formed on the hammer, thereby limiting the advance of the welt. As the hammer is again engaged with the welt the foot 72 is lifted from the welt and is then swung rearwardly into engagement with the stop 108 by the action of the spring 112. It will be noted that the distance which the work may be fed between 120 125 130

the strokes of the hammer is determined by the position of the foot 72 in the direction of feed at the time at which it first engages the welt and that the more advanced in the 5 direction of feed is the initial work engaging position of the foot, the shorter will be the distance which the work may be fed between the strokes of the hammer.

An important feature of the above described feed limiting mechanism is that its 10 construction and mode of operation is such that the operator may control the speed at which the welt is advanced over the upper surface of the welt support within the predetermined speed limit. This enables the operator to advance the welt rapidly up to the 15 predetermined speed limit when operating upon portions of the welt which require a relatively slight beating out and to retard 20 the feed when operating upon those portions which require a more extended beating to cause them to lie flat in the plane of the insole.

As has been stated above, it is desirable 25 when operating upon certain portions of the welt which are particularly refractory, not only to increase the pressure of the welt beating hammer upon the welt, but also to diminish the speed at which the welt is advanced between the welt support and the hammer so that the welt will be subjected to a heavier and more extended beating action. This is particularly true when operating about the toe of the shoe where the curve in the 35 shape of the welt as it extends about the toe tends to draw the outer edge of the welt inwardly so that the welt before being beaten has a warped cross section. In order to cause the initial work engaging position of 40 the feed limiting foot 72 to be advanced in the direction of feed to shorten the distance which the welt may be fed between the strokes of the hammer as the welt support is lifted to increase the pressure of the welt beating hammer upon the welt, the foot is 45 formed with a stop engaging face 118 inclined as shown in Figs. 2, 3 and 4 which engage a correspondingly inclined face on the rear stop 108. The mechanism for raising 50 and lowering the feed limiting foot 72 is constructed and arranged to engage the foot with the work at the same point in the movement of the hammer lever regardless of the vertical position of the welt support. During 55 each cycle of operation of the machine starting at a point when the hammer is engaged with the welt and the feed limiting foot 72 is lifted, as shown in Fig. 2, as the hammer lever moves in a direction to lift the 60 forward end of the lever the frame 76 is actuated by the spring 82 to depress the feed limiting foot 72 into engagement with the work, the pin 92 being held against the upper end of the slot 94 until the feed limiting 65 foot engages the welt which occurs before

the hammer is lifted from the welt. During the continued movement of the hammer lever in the same direction after the foot 72 engages the welt the link 88 rises independently of the pin 92. As the hammer lever swings 70 in an opposite direction to depress its forward end the feed limiting foot is not lifted from the work until the pin 92 engages the upper end of the slot 94, which occurs after the hammer has been brought into engagement with the work. As above explained, the connections between the rocking frame and the bell-crank lever 98-100 are arranged so that changes in the vertical position of the hanger 52 do not affect the angular position of the frame 76 on the shaft 78. It will, therefore, be seen that the forward end of the hammer lever upon which stop 108 is mounted occupies the same absolute vertical position at the time that the feed limiting 80 foot first engages the work, whether the welt support is in raised or in lowered position. This may perhaps be better understood by assuming that the machine is stationary with the parts in the positions which they occupy 90 when the feed limiting foot is first brought into engagement with the work as shown in Fig. 3 and that the work support is then raised to the position shown in Fig. 4. It should be considered that at the time when 95 the feed limiting foot is brought initially into engagement with the work the pin 92 still engages the upper end of the slot 94 and that the link 88 is just about to be lifted to disengage the upper end of the slot from said 100 pin. If, therefore, the parts of the machine are stationary in the positions shown in Fig. 3 and the work support is raised to the position shown in Fig. 4 the feed limiting foot will be still engaged with the welt and the pin 105 92 will remain in engagement with the upper end of the slot 94. This is due to the fact that the frame 76 is mounted upon the hanger 52 so that it swings about the shaft 14 to lift the forward end of the frame with 110 the hanger and that the connections between the frame 76 and the actuating bell crank 98-100, are arranged so that the swinging of the hanger 52 to lift the welt support does not affect the angular position of the frame 115 76, the foot being lifted substantially the same distance as the welt support. Fig. 4, therefore, represents the positions of the parts of the machine when the welt support is raised and the feed limiting foot has been 120 just brought initially into engagement with the work. As shown in Fig. 4, the stop 108 occupies a lower position relative to the inclined face 118 of the feed limiting foot at the time that the foot initially engages the 125 work when the welt support is raised than when the welt support is lowered as shown in Fig. 3. Because of the inclination of the stop engaging face 118 of the feed limiting foot, the initial work engaging position of 130

this foot is advanced in the direction of feed by the raising of the welt support. As the initial work engaging position of the feed limiting foot is advanced in the direction of feed, the distance which the work may be fed between the strokes of the hammer is obviously lessened and the speed at which the work may be fed through the machine is correspondingly decreased.

- 10 In order that the welt slashing knife may be moved vertically with the welt support so that the knife will at all times be in position to act upon the welt as it lies on the upper surface of the welt support, the knife 15 slide 22 is mounted in a suitable guide 120 in the hanger 52 and is held in said guide by a retaining plate 122. With this construction the knife slide swings about the shaft 14 with the hanger 52 and the knife is 20 raised and lowered with the welt support.

Separate treadles may be provided for connection with the treadle rods 50 and 70 to throw the welt slashing knife into and out of operation and to raise and lower the 25 welt support independently. In the preferred construction, however, a single treadle is provided for connection with both of these treadle rods so that the knife is thrown into operation as the welt support is raised 30 to increase the pressure of the welt beating hammer on the welt. In the operation of machines of this type the welt slashing knife is ordinarily thrown into operation only at the toe of the shoe and it is often desirable 35 to increase the pressure of the welt beating means on the welt at portions thereof other than the toe without throwing the knife into operation. To secure these results in the construction illustrated the treadle mechanism 40 is constructed and arranged and connected with the treadle rods 50 and 70 so that upon the depression of the treadle the knife is thrown into operation only after the welt support has been raised to a predetermined 45 position or after a predetermined pressure of the welt beating hammer on the welt is reached. In the construction shown the treadle rod 70 is connected at its lower end with a forwardly extending arm 124 50 fixed to a shaft 126 mounted in bearings in the arms of a bracket 128. The treadle rod 55 50 is threaded at its lower end into a yoke 130 which embraces a second arm 132 fixed to the shaft 126, the yoke carrying a pin 134 which engages in a slot 136 in the arm 132. A treadle 138 is fixed to the end of the shaft 126 by which the shaft is actuated to depress the treadle rods 70 and 50. The pin and slot 60 connection between the yoke 130 and the arm 132 provides for lost motion between the treadle rod 50 and the arm 132 and enables the treadle to be depressed to increase the pressure of the hammer on the welt up to a predetermined amount without throwing the 65 welt slashing knife into operation. When

the treadle is depressed the arm 54, during the first part of the downward movement of the treadle is swung downwardly to raise the welt support and thereby increase the pressure of the hammer on the welt. During this 70 part of the downward movement of the treadle the arm 132 swings downwardly independently of the treadle rod 50 until a predetermined pressure of the welt beating means upon the welt is reached, when the pin 134 engages the upper end of the slot 136 in the arm 132 and the treadle rod 50 is then depressed to swing the arm 42 downwardly and thereby throw the welt slashing knife into operation.

Having explained the nature and object of the invention, and having specifically described a machine embodying the invention in its preferred form, what is claimed is:

1. A welt beating machine having, in combination, welt beating means having an intermittent gripping engagement with the welt, means for varying the pressure of the welt beating means on the welt during the operation of the machine, mechanism for 90 limiting the speed at which the welt may be fed through the machine and means to cause a variation in the limiting speed upon a variation in the pressure of the welt beating means.

2. A welt beating machine having, in combination, welt beating means having an intermittent gripping engagement with the welt, means for limiting the speed at which the welt may be fed through the machine 100 and means for varying the limiting speed during the operation of the machine.

3. A welt beating machine having, in combination, a welt support, welt beating means having an intermittent gripping engagement with the welt, means for varying the pressure of the welt beating means on the welt during the operation of the machine, means for limiting the speed at which the welt may be fed through the machine, and means for 110 causing a decrease in the limiting speed as the pressure of the welt beating means is increased and for causing an increase in the limiting speed as the pressure of the welt beating means is diminished.

4. A welt beating machine having, in combination, a welt support, welt beating means having an intermittent gripping engagement with the welt, means for increasing the pressure of the welt beating means on the welt 120 during the operation of the machine, means for limiting the speed at which the welt may be advanced through the machine and means for causing a decrease in the limiting speed upon increasing the pressure of the welt 125 beating means.

5. A welt beating machine having, in combination, a welt support, welt beating means, pressure varying means, normally inactive welt slashing mechanism, and mechanisms 130

under control of the operator constructed and arranged to be operated in timed relation to each other to actuate the pressure varying means to vary the pressure of the 5 welt beating means on the welt while the welt slashing mechanism is inactive, and to throw the welt slashing mechanism into operation when a predetermined pressure of the welt beating means on the welt is 10 reached.

6. A welt beating machine having, in combination, a welt support, welt beating means, pressure varying means, normally inactive welt slashing mechanism, devices under 15 control of the operator for actuating the pressure varying means to vary the pressure of the welt beating means on the welt while the welt slashing mechanism is inactive, and mechanism arranged to be actuated by said devices in timed relation to the pressure varying means to throw the welt slashing mechanism into operation when a predetermined pressure of the welt beating means on the welt is reached.

25 7. A welt beating machine having, in combination, a welt support, welt beating means, pressure varying means, normally inactive welt slashing mechanism, and connected mechanisms under control of the operator 30 for actuating the pressure varying means to produce variations in pressure while the welt slashing mechanism is inactive, and for throwing the welt slashing mechanism into and out of operation.

35 8. A welt beating machine having, in combination, a welt support, welt beating means having an intermittent gripping engagement with the welt, means for varying the pressure of the welt beating means on the 40 welt during the operation of the machine, means for limiting the speed at which the welt may be fed between the welt support and the welt beating means and means for varying the limiting speed.

45 9. A welt beating machine having, in combination, a welt support, welt beating means having an intermittent gripping engagement with the welt, means for varying the pressure of the welt beating means on the 50 welt during the operation of the machine, means for limiting the speed at which the welt may be fed between the welt support and the welt beating means and connected mechanisms for controlling the pressure 55 varying means and the speed limiting means.

10. A welt beating machine having, in combination a welt support, means for beating the welt having an intermittent gripping engagement with the welt, means for varying the pressure of the welt beating means on the welt during the operation of the machine, means for limiting the speed at which the welt may be fed between the welt support and the welt beating means, and a con-

nection for controlling the speed limiting 65 means arranged to cause a decrease in the limiting speed upon an increase in the pressure of the welt beating means.

11. A welt beating machine having, in combination, a welt support, welt beating 70 means having an intermittent gripping engagement with the welt, means for varying the pressure of the welt beating means on the welt during the operation of the machine and mechanism for limiting the speed at 75 which the welt may be fed through the machine.

12. A welt beating machine having, in combination, a welt support, welt beating 80 means having an intermittent gripping engagement with the welt, means for varying the pressure of the welt beating means on the welt during the operation of the machine, mechanism for limiting the speed at which the welt may be fed through the machine 85 and means for slashing the welt.

13. A welt beating machine having, in combination, a welt support, welt beating means having an intermittent gripping engagement with the welt, means for varying 90 the pressure of the welt beating means on the welt during the operation of the machine, mechanism for limiting the speed at which the welt may be fed through the machine 95 and means under control of the operator and common to both the pressure varying means and the speed limiting mechanism for causing variations in the limiting speed and variations in the pressure of the welt beating means on the welt.

100 14. A welt beating machine having, in combination, a welt support, welt beating means having an intermittent gripping engagement with the welt, a feed limiting foot arranged to be moved by the feed movement 105 of the welt, means for moving the foot into and out of engagement with the welt in timed relation to the welt beating means, and devices for limiting the movement of the foot in the direction of feed.

110 15. A welt beating machine having, in combination, a welt support, welt beating means having an intermittent gripping engagement with the welt, means for varying the pressure of the welt beating means on the 115 welt, a feed limiting foot, mechanism for moving the foot into and out of engagement with the welt in timed relation to the welt beating means, devices for limiting the movement of the foot in the direction of feed 120 comprising a stop and an abutment on the foot, and mechanism for varying the relative positions of the stop and the foot to vary one of the limiting positions of the foot as the pressure of the welt beating means on 125 the welt is varied.

16. A welt beating machine, having, in combination, a vertically movable welt sup-

port, welt beating means having an intermittent gripping engagement with the welt, a hanger movable with the welt support, a feed limiting foot mounted on the hanger 5 for movement with the hanger, means for moving the foot relatively to the hanger into and out of engagement with the welt in timed relation to the welt beating means, and devices for limiting the movement of the 10 foot in the direction of feed constructed and arranged to vary one of the limiting positions of the foot as the foot is raised and lowered.

17. A welt beating machine having, in 15 combination, a vertically movable welt support, welt beating means having an intermittent gripping engagement with the welt, a feed limiting foot movable vertically as the welt support is raised and lowered, and 20 devices for limiting the movement of the foot in the direction of feed comprising a vertically fixed stop and an abutment on the foot, one of which is provided with a contact face obliquely inclined to the vertical, so

that one of the limiting positions of the foot 25 is varied as the foot is raised and lowered.

18. A welt beating machine having, in combination, a welt support, welt beating means arranged to exert normally a predetermined pressure on the welt, normally inactive welt slashing mechanism, means for increasing the pressure of the welt beating means on the welt while the welt slashing mechanism is inactive, and means for throwing the welt slashing mechanism into and 35 out of operation.

19. A welt beating machine having, in combination, a vertically movable welt support, welt beating means, means for moving the welt support vertically to vary the pressure of the welt beating means on the welt, a welt slashing knife arranged to slash the welt while the welt is supported by the welt support, means for supporting the knife for vertical movement with the welt support, 45 and means for throwing the knife into and out of operation.
